UNITED STATES PATENT OFFICE

172,991

BROILER

Fred C. Schwanek, Chicago, Ill., assignor to
Dormeyer Corporation, Chicago, Ill., a corpora-
tion of Illinois

Application January 8, 1953, Serial No. 23,077

Term of patent 14 years

(Cl. D81—10)

To all whom it may concern:

Be it known that I, Fred C. Schwanek, whose full and correct name is Fred C. Schwanek, a citizen of the United States, residing at 5816 North East Circle Avenue, in the city of Chicago, county of Cook, and State of Illinois, have invented a new, original, and ornamental Design for a Broiler, of which the following is a specification, reference being had to the accompanying drawings, forming a part thereof.

Fig. 1 is a front elevational view of a broiler showing my new design;

Fig. 2 is a top plan view thereof;

Fig. 3 is an end elevational view of one end thereof;

Fig. 4 is a front elevational view similar to Fig. 1 with a removable protecting panel on the front side removed;

Fig. 5 is an end elevational view of the other end thereof; and

Fig. 6 is a top view thereof partly in section. The dominant feature of my design resides in the broiler shown in full lines.

I claim:

The ornamental design for a broiler, as shown and described.
